UNITED STATES PATENT OFFICE.

WILLA MABELLE MILLER, OF NINEVEH, VIRGINIA.

BOOK-HOLDER.

1,054,437.

Specification of Letters Patent. Patented Feb. 25, 1913.

Application filed April 4, 1912, Serial No. 688,493. Renewed January 15, 1913. Serial No. 742,312.

To all whom it may concern:

Be it known that I, WILLA M. MILLER, a citizen of the United States, residing at Nineveh, in the county of Warren and State 5 of Virginia, have invented certain new and useful Improvements in Book-Holders; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in book holders and comprises a simple and efficient device of this nature, having various details of construction and combinations and arrangements of parts 20 which will be hereinafter fully described, shown in the accompanying drawings and then specifically defined in the appended claims.

I illustrate my invention in the accompanying drawings, in which:—

Figure 1 is a perspective view of the book holder showing in dotted lines the position that a book would assume when held thereby, and Fig. 2 is an end view of the book 30 holder.

Reference now being had to the details of the drawings by letter, A designates a wire which at B is twisted together forming a loop C, affording a rest for the back of the 35 book as it is held open. Said loop, it will be noted, has two upright portions which are held preferably at an inclination and at the point C' the loop is curved laterally and concaved, the concaved portion being clearly 40 shown in Fig. 1 and the laterally extending portion disclosed in Fig. 2. The back of the book is adapted to engage said concaved portion and serves to assist in supporting the same. The wire adjacent to the twisted part 45 extends laterally in opposite directions, forming a rest to support the device which coöperates with the forwardly projecting portions E, the parts of the wire intermediate the supporting parts being turned into 50 a coil F which also is adapted to rest upon any flat object, as shown in Fig. 2 of the drawings.

Inverted V-shaped portions are formed in the book holder at the ends thereof and the forward portion H of each part thus bent 55 is at an inclination and forms a support for the two covers as disclosed, while the portion I at each end serves as a brace for the cover supporting parts H. Each end of the wire is bent in the form shown in the drawings with a recess K intermediate the end J and the cover supporting portion H, said recess being adapted to support the pages of the book. A pencil rest, designated by letter O, is formed by concaving the upper 65 portion, as illustrated.

In applying a book to my improved holder, the two covers are swung as shown in dotted lines and inserted in the spaces K with the covers resting against the inclined 70 portions H, while the back of the book rests against the loop with the concaved portion at the upper end thereof, said loop C being preferably resilient and held frictionally against the vertical center of the book, thus 75 securely holding the same in open relation.

What I claim to be new is:—

1. A book holder comprising a wire which is bent to form, at its longitudinal center, a loop which is resilient and having its end 80 bent at an angle and concaved for the reception of the back of a book, the portions of the wire adjacent to the opposite end of the loop bent horizontally in opposite directions, thence each bent at right angles forming an 85 inverted, V-shaped portion, the forward part of each forming a support for the cover of a book, the wire thence bent to form a coil and extending forwardly and bent to form an irregular outlined loop, the end of which 90 is positioned parallel with the cover supporting portion of the wire and spaced apart therefrom, as set forth.

2. A book holder comprising a wire which is bent to form, at its longitudinal center, 95 a loop which is resilient and having its end bent at an angle and concaved for the reception of the back of a book, the portions of the wire adjacent to the opposite end of the loop bent horizontally in opposite directions, thence each bent at right angles forming an inverted, V-shaped portion, the forward part of each forming a support for the cover of a book, the wire thence bent to form 100

a coil and extending forwardly and bent to form an irregular outlined loop, the end of which is positioned parallel with the cover supporting portion of the wire and spaced 5 apart therefrom, the upper end of each of said irregular outlined loops being concaved, as set forth.

In testimony whereof I hereunto affix my signature in the presence of two witnesses.

WILLA MABELLE MILLER.
